UNITED STATES PATENT OFFICE.

ALFRED F. SANFORD, OF KNOXVILLE, TENNESSEE.

RADIO APPARATUS.

Application filed August 18, 1925. Serial No. 51,067.

This apparatus relates especially to means for bringing a radio-receiving apparatus into tune with the sending apparatus at different sending stations.

5 An object of this invention is to associate with the tuning members of a radio-receiving apparatus means for moving the tuning members into positions whereby they are brought into tune with a sending apparatus of chosen 10 sending stations, the receiving apparatus including members bearing record receiving surfaces and movable in fixed relation with the tuning members, to the end that when the tuning members have been moved into positions bringing those members into tune with the sending apparatus of a chosen sending station, suitable records may then be made 15 on the record-receiving surfaces, which records then stand in fixed relation to the then 20 positions of the tuning members, so that thereafter those tuning members may be again brought into tune with the apparatus of that sending station by moving said tuning members until the records of said record-receiving surfaces are again in the position in 25 which they were made. It might also be said that the members bearing the record-receiving surfaces may be moved until those records are again in the positions in which they 30 were made. For, as already stated, there is to be a fixed relation between the tuning members and the members bearing the record-receiving surfaces.

The apparatus illustrated and described by 35 this application comprises three tuning shafts and three wheels of equal diameter and on a common axial line and each bearing on its perimeter a record-receiving surface. One of said surfaces is to receive records concerning 40 one of the tuning shafts; another of said surfaces is to receive records concerning another of the tuning shafts; and the third of said surfaces is to receive records concerning the third of said tuning shafts.

45 These wheels are rotatable independently of each other and each wheel is connected by gearing to one of the tuning shafts, whereby the turning of said wheel will cause the turning of said shaft. The wheels are of sufficient diameter to produce a circumference 50 of such dimension as will provide a long record-receiving surface. Furthermore, this extended circumference will allow a relatively large part of said circumference to pass a 55 given point during a relatively small fractional movement of the corresponding tuning

shaft, whereby record-receiving space will be available for noting sending stations with which the receiving mechanism may be brought into tune by very slight turning 60 movement of the tuning shaft.

In the accompanying drawings,

Fig. 1 is a front elevation of a radio-receiving apparatus embodying my improvement, the upper part of the front wall of the body 65 of the apparatus being broken away to expose the interior mechanism;

Fig. 2 is an upright section on the axial line of the wheels which bear record-receiving surfaces and from which wheels motion is 70 transmitted to the tuning shafts;

Fig. 3 is a detail section on the line, 3—3, of Fig. 1, looking toward the left;

Fig. 4 is an upright section on the line, 4—4, of Fig. 1 looking toward the left; 75

Fig. 5 is an upright section on the line, 5—5, of Fig. 1, looking toward the left;

Fig. 6 is an upright section on the line, 6—6, of Fig. 1, looking toward the left;

Fig. 7 is an upright section on the line, 80 7—7, of Fig. 1, looking toward the left.

Referring to said drawings, A is the front wall of the apparatus. A¹ is the base and A² is the top of the apparatus. A³ is the right hand end wall. A⁴ is the left hand end wall. 85

The wall, A⁴, is also the right hand wall of the compartment for the record-receiving wheels. A⁵ is the left hand wall of that compartment. A⁶ is the top wall of that compartment. A⁷ is the front wall of that compartment. 90

An inner upright wall, A⁸, is parallel to the front wall, A, and forms a support for the tuning shafts, B, C and D, and the gearing associated with those shafts. Each of said shafts has a bearing in the wall, A⁸, and projects forward through said wall. On the 95

forward end of the shaft, B, is fixed a bevel gear wheel, B¹, which meshes with a smaller bevel gear wheel, B², which surrounds and is fixed on the horizontal drive shaft, B³, 100

which rests in two bearings, B⁴, seated on the front face of the wall, A⁸. The shaft, B³, extends toward the left through the record wheel compartment and has its left hand end resting in a bearing, B⁵, which bearing is seated in the record compartment wall, A⁵. Adjacent the wall, A⁵, a record-receiving wheel, B⁶, surrounds and is fixed to said shaft by means of a set screw, B⁷.

If this wheel is rotated, the shaft, B³, and 110 the bevel gear wheel, B², are also rotated. Rotating the bevel gear wheel, B², causes the

rotation of the bevel gear wheel, B¹, and the tuning shaft, B.

A spur gear wheel, C¹, surrounds and is fixed to the forward end of the tuning shaft, C. That spur gear wheel meshes with a spur gear wheel, C², which is integral with the hub of the bevel gear wheel, C³, which surrounds and is fixed on the rotatable shaft, C⁴, which is seated in the bearing, C⁵, which 10 is seated in the wall, A⁸. The bevel gear wheel, C³, meshes with a bevel gear wheel, C⁶, which surrounds and is fixed on the shaft, C⁷, which is parallel to the shaft, B³, and rests in three bearings, C⁸, seated on the front face 15 of the inner wall, A⁸, above the level of the shaft, B³. A spur gear wheel, C⁹, surrounds and is fixed to the shaft, C⁷, at the left of the left hand bearing, C⁸. That spur gear wheel meshes with a similar spur gear wheel, 20 C¹⁰, which surrounds and is fixed on the sleeve, C¹¹, which loosely surrounds the shaft, B³. Said sleeve extends nearly to the hub of the wheel, B⁶. A record-receiving wheel, C¹², surrounds said sleeve and is fixed thereto by 25 means of a set screw, C¹³. Turning the wheel, C¹², will cause the turning of the sleeve, C¹¹, and the spur gear wheel, C¹⁰. That will cause the turning of the spur gear wheel, C⁹, the shaft, C⁷, the bevel gear wheel, C⁶, and the 30 bevel gear wheel, C³, whereby the spur gear wheels, C² and C¹, and the tuning shaft, C, are turned.

A spur gear wheel, D¹, surrounds and is fixed to the forward end of the tuning shaft, 35 D, and meshes with a spur gear wheel, D², which is integral with the hub of the bevel gear wheel, D³, which surrounds and is fixed to the shaft, D⁴, which is rotatable in the bearing, D⁵, which is seated in the wall, A⁸. The bevel gear wheel, D³, meshes with the 40 bevel gear wheel, D⁶, which surrounds and is fixed on the shaft, D⁷, which is parallel to and below the level of the shaft, B³, and rests rotatably in three bearings, D⁸, which are supported on the front face of the wall, A⁸.

A spur gear wheel, D⁹, surrounds and is fixed to the left hand end of the shaft, D⁷, and meshes with a spur gear wheel, D¹⁰, which surrounds and is immovably fixed on the sleeve, D¹¹, which loosely surrounds the sleeve, C¹¹. The wheel, D¹², the third of the record-receiving wheels, surrounds the sleeve, D¹¹, and is immovably secured thereto by 50 means of the set screw, D¹³.

Turning the wheel, D¹², will cause the turning of the sleeve, D¹¹, the spur gear wheels, D¹⁰ and D⁹, and the shaft, D⁷, and the bevel gear wheels, D⁶ and D³, and the spur gear wheel, D², whereby the spur gear wheel, D¹, and the tuning shaft, D, are turned.

The sleeve, C¹¹, is to fit so loosely on the shaft, B³, and the sleeve, D¹¹, is to fit so loosely on the sleeve, C¹¹, as to permit turning 65 any of the wheels without turning another

through frictional engagement between the shaft, B³, and the sleeves.

The forward upper part of the compartment in which the record-receiving wheels are located is open to expose those wheels to view and to permit them to be grasped by the hands of the operator to turn those wheels.

The operation is as follows:

When this receiving apparatus is to be brought into tune with a chosen sending station, any one of the three record-receiving wheels, B⁶, C¹² and D¹², is engaged by the hand of the operator and turned until the tuning shaft associated with that wheel is in tune, it being understood that the operator stands at the front of the apparatus. Then another of said wheels is turned in the same manner until the tuning shaft associated with that wheel is in tune. Then the third of said wheels is similarly turned until the tuning shaft associated with that wheel is in tune. Then a record identifying that sending station is placed on the perimeter of each of the three wheels. This record is to be made in association with a relatively stationary 90 guide or indicator. That guide or indicator might be the upper edge of the front wall, A⁷, of the record wheel compartment. The drawings show a guide or indicator, A⁹, having a foot, A¹⁰, seated on the upper edge of the front wall, A⁷, the foot being secured by means of screws, A¹¹. Thus the body of this indicator is brought close to the face of the wheels. The upper edge of this indicator or guide may be used for placing the record of the sending station on the wheels immediately above the indicator. But the drawing shows the body of the indicator slotted, whereby a definite space on the wheel faces is exposed for receiving the record. Thus the operator has the choice of placing the records into the slot or immediately above the upper edge of the indicator. The record made on each wheel is to identify the sending station. The record may consist of the name or the symbols representing the sending station, or both the name and the symbols may be used. Fig. 1 of the drawings shows in the slot space, as a record, "MIAMI-WMBF", on each of the three wheels.

If the apparatus is to be brought into tune with another sending station, the wheels are to be turned successively until each of the three tuning shafts is in tune with the new sending station. Then a record identifying that record-receiving station is placed on the wheels in the manner already described. When it is desired to again bring the receiving apparatus into tune with a sending station with which this apparatus has been previously brought into tune, the three wheels are turned to bring the records identifying that sending station again into position at the guide or indicator, A⁹.

It is to be observed that the recording sur-

face on each wheel is as long as the circumference of that wheel. This makes a record-receiving surface which is long relative to the length of the path through which the tuning mechanism supported by the tuning shaft turns. Thus two important results are attained. (1) A long movement of the wheel surface imparts to the tuning shaft and the mechanism supported by the shaft a movement which is much shorter. This makes possible action similar to micrometer action for the adjustment of the tuning shaft; (2) this long recording surface provides ample room for the entry of records of receiving stations which require nearly the same positions of the tuning shafts.

The gearing between each of the wheels, B⁶, C¹² and D¹², and the corresponding tuning shafts is to be so proportioned as to allow the wheels to turn faster than the corresponding tuning shafts turn. This ratio is preferably two to one, so that each wheel will make a full turn while the corresponding tuning shaft makes only one-half turn. Thus the entire perimeter of each wheel is made available for recording.

It is to be understood that instead of making records directly on the perimeter of the wheels, paper or similar sheet-form material may be applied to the surface of the wheels and records placed on that material.

I claim as my invention:

1. In an apparatus of the kind described, the combination with a plurality of tuning shafts, of a plurality of members shiftable independently of each other and having record-receiving surfaces, a transmission shaft for each of the tuning shafts, gearing connecting each of said transmission shafts with one of the tuning shafts, and gearing connecting each of said transmission shafts with one of said shiftable members, whereby moving one of said shiftable members will cause transmission of motion to the corresponding tuning shaft, substantially as described.

2. In an apparatus of the kind described, the combination with a plurality of tuning shafts, of a plurality of members shiftable independently of each other and having record-receiving surfaces, parallel transmission shafts, gearing connecting each of said transmission shafts with one of the tuning shafts, and gearing connecting each of said transmission shafts with one of said shiftable members, whereby moving one of said shiftable members will cause transmission of motion to the corresponding tuning shaft, substantially as described.

3. In an apparatus of the kind described, the combination with a plurality of tuning shafts, of a plurality of members shiftable independently of each other on a common axial line and having record-receiving surfaces, a transmission shaft for each of the tuning shafts, gearing connecting each of said

transmission shafts with one of the tuning shafts, and gearing connecting each of said transmission shafts with one of said shiftable members, whereby moving one of said shiftable members will cause transmission of motion to the corresponding tuning shaft, substantially as described.

4. In an apparatus of the kind described, the combination with a plurality of tuning shafts placed on parallel axial lines, of a plurality of record-receiving wheels located in parallel planes and on a common axial line, transverse to the axes of the tuning shafts and gearing connecting each of said wheels with one of the tuning shafts whereby provision is made for the turning of the tuning shafts by turning said wheels, substantially as described.

5. In an apparatus of the kind described, the combination with a plurality of tuning shafts placed on parallel axial lines, of a plurality of record-receiving wheels located in parallel planes and on a common axial line, a plurality of parallel transmission shafts one of which is located between each wheel and one of the tuning shafts and in operative relation with said wheel, and gearing connecting said transmission shaft and said tuning shaft, substantially as described.

6. In an apparatus of the kind described, the combination with a plurality of tuning shafts placed on parallel axial lines, of a plurality of members located side by side and having endless record-receiving surfaces, and gearing including bevel cog wheels connecting said members with said tuning shafts, substantially as described.

7. In an apparatus of the kind described, the combination with a plurality of tuning shafts placed on parallel axial lines, of a plurality of members located side by side and having endless record-receiving surfaces, of equal length, and gearing including bevel cog wheels connecting said members with said tuning shafts, substantially as described.

8. In an apparatus of the kind described, the combination with a plurality of tuning shafts placed on parallel axial lines, of plural record-receiving mechanism comprising parts having record-receiving surfaces and adapted to be moved through orbital paths, and means including bevel cog wheels connecting the record-receiving mechanism with the tuning shafts whereby the tuning shafts will turn while the record-receiving mechanism is actuated to move the record-receiving surfaces in the orbital paths, substantially as described.

9. In an apparatus of the kind described, the combination with a plurality of horizontal tuning shafts placed on parallel axial lines, of a plurality of transmission shafts transverse to the tuning shafts, bevel gearing connecting the transmission shafts to the tuning shafts, record-receiving wheels lo-

cated on a common axial line and in operative relation with the transmission shafts, substantially as described.

10. In an apparatus of the kind described, 5 the combination with a plurality of tuning shafts, of a plurality of transmission shafts in operative relation with the tuning shafts, a record-receiving wheel fixed on one of said transmission shafts, a sleeve surrounding a 10 part of said transmission shaft, a wheel surrounding said shaft and fixed to said sleeve, a transmission shaft in operative relation with said sleeve and one of the tuning shafts, a second sleeve surrounding the first sleeve, a 15 record-receiving wheel surrounding the first sleeve and secured to the second sleeve, and means operatively connecting the second sleeve and another tuning shaft, substantially 20 as described.
20. 11. In an apparatus of the kind described, the combination with a plurality of tuning shafts placed on parallel axial lines, of a corresponding number of members having record-receiving surfaces arranged to travel 25 in paths located in planes which are parallel to each other and to the tuning shafts, and transmission means connecting said record-receiving members with the tuning shafts.
30. 12. In an apparatus of the kind described, 30 the combination with a plurality of tuning

members, of a corresponding number of tuning member actuating wheels placed upright and parallel to each other and near each other and in planes perpendicular to the front of 35 the apparatus and having their perimeter faces directed toward the front of the apparatus and in location to be conveniently reached and engaged either singly or together by a hand of the operator for separately or simultaneously turning said wheels for adjusting the tuning members, and each wheel being of a long circumference and having a perimeter of width and nature adapted for writing thereon records of positions of the tuning member positions when said members have been positioned in harmony with each other and in tune with a chosen sending station, said writing being horizontal and transverse to the perimeter face and in relation 40 to a stationary part of the apparatus, means in operative relation with one of said wheels and one of said tuning members for transmitting motion from said wheel to said tuning member, and means in operative relation 45 with another of said wheels and another tuning member for transmitting motion from said wheel to said tuning member.

In testimony whereof I have signed my name, this 1st day of August, in the year one 50 thousand nine hundred and twenty-five.

ALFRED F. SANFORD.
